UNITED STATES PATENT OFFICE.

JOHN M. YOUNG, OF BROOKLYN, NEW YORK, ASSIGNOR TO AMERICAN CAN COMPANY,
OF NEW YORK, N. Y., A CORPORATION OF NEW JERSEY.

CONTAINER.

Application filed May 22, 1922. Serial No. 562,898.

This invention relates in general to tearing strip cans and has more particular reference to cans of the character of that of my co-pending application Serial No. 525,600, filed December 27, 1921. In that application two score lines are formed on the outside of the can body to define the strip and within this can is provided a band tightly engaging the material of the body and extending from beneath the lower score line to well above the upper. This strip is in liquid-tight fit with the container. When the tearing strip is removed the cover and upper part of the body form a flanged slip cover adapted to embrace the top of the internal band or strip.

It is a principal object of my present invention to provide a can of this character in which the tearing strip may be more readily removed and to this end I have provided the score lines upon the inner surface of the can. In removing the strip it is pulled outwardly either by the hand or by winding it about a key and severance more readily accomplished where the lines of scoring are arranged on the inside so that the fracture is continually started as the strip is unwound from the can and wound upon the key.

A further and important object of the invention is the provision of a can of this character in which may be packed acid food and other products, arrangement being made to prevent the acid or other content from attacking the material of the can at the scoring. It will be understood in this connection that the scoring of the can particularly upon the inside, does or may expose the black metal (iron) directly to the attack of the acid. My invention contemplates in this regard the provision of an internal band in such arrangement as to seal the scoring lines and adjacent areas from contact with the content of the container.

Numerous other objects and advantages of the invention will be apparent as it is better understood from the following description, which, taken in connection with the accompanying drawings, discloses a preferred embodiment thereof.

Referring to the drawings,

Fig. 1 is a perspective view of a can embodying my present invention;

Fig. 2 is an enlarged section showing the same before the tearing strip has been removed;

Fig. 3 is a similar view with the slip cover raised after the tearing strip has been removed; and

Fig. 4 is a partial perspective showing a preferred manner of connecting the ends of the internal band or strip.

On the drawings, reference character 11 indicates a can body to which is seamed or otherwise secured a top or cover 12 in any usual or preferred fashion, the seam in the present instance being the ordinary double seam employed in process cans. Score lines 13 are provided circumferentially of the can and define between them a tearing strip 14 which preferably terminates at a tongue 15 extending beyond a side seam 16. Diagonal score lines 17 may be provided, if desired, to direct the lines of tear back to the core lines 14 should there be a tendency to tear inwardly from them. An internal continuous band 18 of sheet tin, having its ends connected, is tightly fitted in place and covers the score lines 13 and extends beneath the lower score line a sufficient distance to provide a permanent engagement and acts to confine the liquid content against spilling after the tearing strip 14 has been removed. The ends of the band are or may be joined by a lock seam, as at 20 in Fig. 4. In such a seam the ends are hooked and interfolded and the entire seam is located inwardly of the outer plane of the band. A mere line is disposed across the outer face of the band and this may be closed with solder if desired, although in the ordinary instance this is not thought necessary.

The removal of the tearing strip leaves a flange 19 (Fig. 3) extending down from the top 12 so that the top and flange constitute a slip cover adapted to be positioned and removed as occasion may render desirable after the can has been once opened.

It is thought that the invention and many of its attendant advantages will be understood from the foregoing description, and it will be apparent that various changes may be made in the form, construction and arrangement of the parts without departing from the spirit and scope of the invention or

sacrificing all of its material advantages, the form hereinbefore described being merely a preferred embodiment thereof.

I claim:

5 A can comprising a body having a top closure, and provided with internal scoring therebeneath adapted to permit severance of a tearing strip from the can to open it, and a band having its ends connected in a lock

seam and presenting a smooth substantially 10 continuous outer face in contact with the body, said band being arranged circumferentially within the can and in tight metal-to-metal fit with its inner wall and adapted to protect said scoring from contact with the 15 liquid content of said container.

JOHN M. YOUNG.
